MULTIPLE GAME BOARD

William A. Squiers, 1329 W. Maple St.,
Kalamazoo, Mich. 49008

Filed Dec. 10, 1973, Ser. No. 423,252

Term of patent 14 years

Int. Cl. D21—01

U.S. Cl. D34—5 SS

Fig. 1

Fig. 2

Fig. 3

Fig. 4

Fig. 5

FIG. 1 is a top plan view of a multiple game board embodying my new design;

FIG. 2 is a rear elevational view thereof;

FIG. 3 is a side elevational view thereof;

FIG. 4 is a top plan view of an additional embodiment of a multiple game board embodying my new design; and

FIG. 5 is still another embodiment of a multiple game board embodying my new design.

I claim:

The ornamental design for a multiple game board, as shown and described.
